UNITED STATES PATENT OFFICE.

OSCAR W. ALLISON, OF ROCHESTER, NEW YORK.

CIGARETTE-MACHINE.

SPECIFICATION forming part of Letters Patent No. 231,947, dated September 7, 1880.

Application filed April 22, 1880. (No model.)

To all whom it may concern:

Be it known that I, OSCAR W. ALLISON, of Rochester, Monroe county, New York, have invented certain Improvements in Cigarette-Machines, of which the following is a specification, reference being had to the accompanying drawings, in which—

Figure 1 is a plan view of my improved cigarette-machine. Fig. 2 is a side elevation 10 of the same. Fig. 3 is a plan view of the paper-folder. Fig. 4 is an end view of the same. Fig. 5 is a side elevation of the tobacco-rod-forming wheel and its attachments. Fig. 6 is a plan view of the forming-wheel. Fig. 7 is a 15 side elevation of the eccentric for operating sliding tobacco-carriers. Fig. 8 is a vertical section through the rod-forming wheel on the line *x* *x*, Fig. 6. Fig. 9 is a section through the rim of said wheel on the line *y* *y*, Fig. 5. Fig. 10 is a section through the rim of said 20 wheel and the trimming-wheel on the line *o* *o*, Fig. 5. Fig. 11 is a section on the line *z* *z*, Fig. 5. Fig. 12 is an end view of the machine, showing the knife and endless belt provided 25 with hoppers. Fig. 13 represents the knives for cutting the cigarette-tube.

My invention relates to an improved cigarette-machine in which the tobacco is fed onto a revolving rod-forming wheel provided with 30 suitable guiding and compressing attachments, whereby the tobacco is formed into a continuous compacted rod, about which an endless web of paper is folded by suitable mechanism, and the continuous cigarette thus formed is 35 fed forward by carrying-rolls and delivered to an automatic dividing-knife, by which it is severed into suitable lengths for cigarettes; and my invention consists in the rod-forming wheel and attachments, and in the combination 40 of the various devices above specified, and in the mechanical details of the apparatus, as hereinafter more fully described.

My improved cigarette-machine is shown in the accompanying drawings, in which A is a supporting-table; B, the feed-board; C, the rod-forming wheel; D D' and E E', the grooved carrying-rolls; F F', the discharge-rolls, and G the knife. Q represents a roll of paper, and r a pasting-wheel.

Power is applied to the pulley J, Fig. 1, and its motion is transmitted to the various moving parts.

In the operation of the machine tobacco is fed by hand from the feed-board onto the forming-wheel, by the operation of which and its attachments the tobacco is formed into a continuous rod, about which a web of paper previously gummed on one edge is folded by the folder *a*, after which the cigarette enters and is fed onward by the carrying-rolls passing 60 through the drier R, and being finally delivered from the moisture by the last pair of rolls to the dividing-knife G. A continuous cigarette is thus formed at a high rate of speed, which is severed into cigarettes of any desired 65 length by the automatic operation of the knife.

The feed-board B receives the tobacco which is to be fed through the machine. It may be slightly inclined to facilitate the feeding operation, and the tobacco is placed on it in convenient quantities and fed regularly by hand into the hopper.

The wheel C is supported by suitable standards *b* *b'* rising from the table A. It is provided with a rim, which projects laterally on 75 one side of the spokes. The rim is provided with a groove, *e*, about its circumference, which groove has a semicircular bottom, and is made of the size of the tobacco-rod of which the cigarette is to be formed.

On each side of the rod-forming groove *e* are 80 narrower grooves *ff'*, Figs. 9, 10, and 11, in which are fitted the guard-plates *g* and *g'*, (see Fig. 1,) the latter being attached to the feed-board B.

Inside of the wheel is placed the eccentric L, which is held stationary by the rod *h*, attached to one of the wheel-supporting standards *b* *b'*, or by any other convenient arrangement. The wheel-hub M may be fitted to turn 90 within the eccentric, in which case it also serves to support it.

On the outside of the eccentric is fitted a ring, N, which revolves with the wheel. To the ring N are attached a number of radial 95 sliding rods, *i* *i* *i*, which pass through holes drilled through the rim of the wheel in the center of the groove *e*. The rods *i* *i* are round and reduced to a fine point at their outer ends. They perform the office of feeding the tobacco, 100 but are withdrawn from it at the lower side of the forming-wheel, so that the tobacco-rod is continuous and without break. As the wheel revolves these rods draw the ring N with it,

and they are by it compelled to slide in and out through the rim. The rods project from the rim of the wheel a short distance on the upper side of it, but on its lower side they are drawn in by the eccentric, so that their points are entirely concealed within the bottom of the groove *e*.

When the wheel revolves in the direction represented by the arrows in the drawings, 10 the tobacco, being fed from the feed-board by hand onto the wheel, is forced forward by the radial sliding rods *i i* into the guide *j*, Figs. 5 and 8. The guide *j* is composed of a curved strip of metal, the edges of which are fitted 15 into the grooves *f f'* on the rim of the wheel. (See Fig. 9.) The inner surface of the guide *j* is not concentric with the wheel, but it is so placed with reference thereto that the space between the two is greatest at the point where 20 the tobacco enters the guide, and diminishes from there onward, so that the tobacco is gradually gathered together and packed as it progresses through the guide.

The guide is supported in the proper relation 25 with the forming-wheel by the vertical standards *k k'*, which arise from the table *A*, and also carry the trimming-wheel *O* and the compressor *P*. The trimming-wheel *O* is shown in relation to the wheel and groove in the section, 30 Fig. 16. It consists of a small wheel of such thickness as to just fit within the groove *e*, and having a semicircular groove about its periphery. Its office is to compress and condense the stream of tobacco delivered to it from the 35 guide *j* by the sliding rods *i i*, and also to cut off any excess of tobacco, for which purpose its edges are made sharp and are preferably hardened.

The tobacco, after passing the trimming-wheel *O*, is now subjected to the action of the 40 compressor *P*, which is a curved bar of a width to fit closely within the groove *e*, and having a semicircular channel on its upper surface. The compressor *P* is supported by suitable 45 braces extending inward from the standards *K K'*, and it reaches from immediately below the trimming-wheel *O*, on the side of the wheel *C*, to a point a short distance beyond the bottom thereof. It is so placed as to be closer to 50 the wheel *C* at its lower point than it is near the trimming-wheel, so that as the tobacco passes through the groove *e*, between the compressor and the wheel, it is gradually further compressed and condensed. This operation is 55 facilitated by the fact that as the tobacco passes through the compressor the rods *i i* are being gradually withdrawn from it and concealed within the wheel *C*, so that the force necessary to crowd the material through is necessarily 60 derived from those portions thereof which are coming into the compressor from behind, under the action of the sliding rods. The result is that the stream of tobacco is packed and condensed in the compressor, so that it is delivered therefrom at the bottom of the wheel 65 in the form of a compacted straight rod of

suitable shape and size to form cigarettes when wrapped with paper.

The rod of tobacco would remain in the groove *e* and be carried around the wheel if 70 not removed therefrom. To effect this operation I provide a scraper, *l*, Figs. 5 and 8, which is a bent metallic bar attached in any convenient way to any part of the machine which will afford its support, and which extends 75 into the groove *e*, and terminates near the end of the compressor in a sharp edge. The point of the scraper is fitted to the groove on its upper side, and its lower side is hollowed or shaped to fit the rod of tobacco passing beneath it.

By the operation of the scraper the tobacco-rod is disengaged from the groove *e* and caused to pass forward on the compressor, from which it is delivered to the table *m*, which supports 85 the paper-folder *a*. From the paper-folder the cigarette-rod, wrapped in paper from the endless web of paper on the roll *Q*, passes between the carrying-rolls *D D'* and *E E'*, and thence through the drier *R* to the discharge-rolls *F F'*. These rolls are preferably faced 90 with soft rubber, and they have semicircular grooves worked in their faces of a size corresponding with that of the cigarette-rod. I prefer also to place the axes of one set of rolls, 95 *D D'*, at right angles with the other set, *E E'*, as by this arrangement any creases or folds in the paper envelope caused by the first set of rolls are pressed out by the second set.

The drier *R* consists of a double cylinder, 100 into which steam is admitted when the machine is in operation for the purpose of drying the cigarette-rod.

The course of the cigarette-rod through the machine is indicated by dotted lines in the 105 drawings, Figs. 1 and 2.

a', Fig. 2, represents a pipe for supplying steam for the drier. Where steam cannot be obtained the drier may consist of a metallic plate or trough, heated by a fire in any convenient manner.

The operation of covering the tobacco-rod, after it has been formed by the forming-wheel *C*, with an envelope of paper is performed in the following manner:

An endless web of paper, *Q*, Figs. 1 and 2, is supported by brackets attached to the table *A*, and from it the paper is led over the rollers *n n'*, and thence to the paper-folder *a*, as indicated by the dotted lines in Fig. 2. The 115 roller *n'* should be located above the folder, in order to give the paper a tendency to fold into a tube. A pasting-roll, *r*, dips into the trough *s*, which contains paste, and in revolving applies the paste or gum to one edge of the endless web of paper as it passes over the roller *n'*.

The paper-folder is composed of two hollow inclined wings of suitable shape interiorly to form the endless web of paper into a tube. It is shown in plan view in Fig. 3 and in 130 front elevation in Fig. 4, and it is located in the proper position to fold the paper about the

formed tobacco-rod as it leaves the compressor P. The wings of the paper-folder may be attached on each side to the supporting-plate m by slotted lugs, in order to permit of the adjustment of the wings to and from each other; but they should not be so placed as to cause any friction on the paper. The wings operate merely to fold the paper about the formed rod of tobacco, in a manner similar to that in which 10 the wings or fingers in paper-bag machines operate to fold the paper about the former-bar in such machines. The adhesion of the pasted edge of the paper to the outer edge is secured by a spring-finger, t, Figs. 2 and 3, bearing 15 lightly on the cigarette-rod after it has left the folder a, in the manner of producing this result in paper-bag machines.

The grooved rollers D D' and E E' are so shaped as to cause as little pressure as possible on the pasted edge, to prevent the paste from being squeezed out from between the fold of the paper. From the carrying-rolls D D', on the shaft of one of which the driving-pulley J is placed, power is transmitted to the 25 rod-forming wheel C and the remaining rolls by any convenient system of gearing, as illustrated in the drawings at u u' u'', Fig. 1.

After leaving the feed-rolls F F', the cigarette passes over the stationary knife G', on which 30 it is severed into suitable lengths for smoking by the rotary knife G. The rotary knife G is attached to a shaft, v, Fig. 1, which is driven from any convenient moving part of the machine at a suitable speed with reference to the feed-rolls to divide the cigarette into the desired length. The edges of the knives G G' are preferably notched and serrated at the point where the cigarette passes between them, as shown in Fig. 13.

40 The finished cigarettes are received, as they drop from the knives G G', in the hoppers w w on the endless belt T. The belt T runs over pulley U on the shaft y, which is driven from the feed-rolls F F' by bevel-gearing. The 45 hoppers w w are not closed on the side next the feed-rolls, and by proportioning the speed of the belt T to that of the feed-rolls the cigarettes may be divided into bunches of any desired number. The motion of the belt T may 50 be either continuous or intermittent.

In order to control any irregularity in the feeding of the tobacco, I employ an adjustable feeding-gate placed between the guard-plates immediately before the entrance into 55 the guide j. This gate is represented at h', Figs. 5 and 8, and consists of a plate arranged to slide radially to and from the forming-wheel.

The feed-board B may have a shaking motion given to it by an eccentric or cam for the 60 purpose of facilitating the feeding operation.

Any excess of tobacco trimmed off by the wheel O is received into any suitable recepta-

cle, and from thence returned to the feed-board.

I claim—

1. In a cigarette-machine, the tobacco-rod-forming wheel C, having peripheral groove e and sliding rods i i, substantially as described. 65
2. In combination with the forming-wheel C, having groove e and sliding rods i i, the trimming-wheel O, substantially as described. 70
3. The combination of the forming-wheel C, having groove e and rods i i, with the feed-board B, substantially as described. 75
4. The combination of the forming-wheel C, having groove e and sliding rods i i, feed-board B, and adjustable gate h', substantially as described. 80
5. The forming-wheel C, having peripheral groove and feeding-rods, with the guide j and trimming-wheel O, substantially as described. 85
6. The combination of the grooved rod-forming wheel C, having sliding rods i i, compressor P, and scraper l, substantially as described. 90
7. The combination of the grooved rod-forming wheel C, having sliding rods i i, and the compressor P, substantially as described. 95
8. The combination of the grooved rod-forming wheel C, having sliding rods i i, feed-board B, guide j, trimming-wheel O, compressor P, and scraper l, substantially as and for the purposes set forth. 100
9. The combination, in a cigarette-machine, of the grooved rod-forming wheel C, having sliding feeding-rods i i, guide j, compressor P and scraper l, and the paper-folder a, substantially as described. 105
10. The combination of the rod-forming wheel C, having suitable feeding and compressing attachments, the paper-folder a, and carrying-rolls D D', substantially as described. 110
11. The combination of the rod-forming wheel C, having suitable feeding and compressing attachments, paper-folder a, carrying-rolls D D', and drier R, substantially as set forth. 115
12. The combination of the revolving forming-wheel C, having sliding rods i i, and the guide j, substantially as described. 120
13. In combination with a cigarette-machine having rod-forming wheel C, provided with sliding feeding-rods i i, compressor P, and scraper l, paper-folder a, carrying-rollers and dividing-knife, the automatically-operating counting-hoppers w w, substantially as described. 125
14. In combination with the rod-forming wheel C, having sliding feeding-rods i i, compressor P, and scraper l, the paper-folder a and pasting-finger t, substantially as described. 130

OSCAR W. ALLISON.
